UNITED STATES PATENT OFFICE.

LEWIS H. BROOME, OF JERSEY CITY, NEW JERSEY.

WHEEL-TIRE.

No. 833,487.

Specification of Letters Patent.

Patented Oct. 16, 1906.

Application filed August 28, 1905. Serial No. 276,087.

To all whom it may concern:

Be it known that I, LEWIS H. BROOME, a citizen of the United States, and a resident of Jersey City, in the county of Hudson and State of New Jersey, have invented certain new and useful Improvements in Wheel-Tires, of which the following is a specification.

This invention has reference to vehicle-wheels, and relates more particularly to the tire equipment of the same.

Prominent objects of the invention contemplate a high cushioning effect, great durability combined with comparative simplicity of construction, facility for application, removal, and repair, and minimum heating and chafing of parts.

With the above and other purposes in view the improvements primarily involve a tire comprising a longitudinally-curved tubular element of stiff resilient material adapted to be circumferentially disposed relative to a wheel, said element being longitudinally split or divided at one side to present edge portions, one of which is capable of a free movement with respect to the other under the compression and expansion which the tubular element undergoes while in use, together with a casing or covering of yielding material, and provision for positively securing the inner portion of said element in position on the wheel. A development of the tubular element involves making the same of spring metal and in the form of a ring, with 35 the split or division continuous at the side.

The improvements further comprehend a tubular element of stiff resilient material capable of being disposed as stated and provision for positively securing the tubular element in position, together with an incasing shoe of yielding material adapted to be removed independently of said element.

Novel provision is made for adapting the improvements for embodiment in tires designed for different conditions of service and also in connection with pneumatic tires as well as those of the cushion type.

There are numerous other important features connected with the invention, which, in addition to those previously referred to, are clearly set forth in the subsequent detailed description.

In the accompanying drawings, forming part of this specification, Figure 1 is a vertical transverse sectional view illustrating one

form of my invention. Fig. 2 is a detail vertical sectional view of the construction represented in Fig. 1, the plane of section being a central one, as indicated by the broken line 22 of the last-mentioned figure. Figs. 3 to 7, inclusive, are views somewhat similar in character to Fig. 1, but illustrating some of the many additional forms of which the invention is susceptible. Figs. 8 and 9 are detail views illustrating the manner in which the tubular ring is secured when employed in connection with a pneumatic tire. Fig. 10 is a detail sectional view illustrating the relation of the wedge with the slotted bolt and one of the clamp-plates of the construction disclosed in Fig. 7.

Similar reference characters designate corresponding parts in the several figures of the drawings wherein they occur.

Considering for the present the first two figures, 10 designates a tubular spring-metal ring which may be produced in any suitable manner. For example, said ring may be formed by transversely curling a comparatively narrow section or strip of sheet-steel of the required length so that it will acquire a tubular or approximately tubular shape, the section as thus conditioned being subsequently subjected to a bending operation to convert it into a ring, the section ends being united by brazing or welding, the latter operation being preferably conducted electrically, so as to prevent to the greatest possible extent the heat from impairing the metal for the particular service for which it is to be used. In the form of incomplete tube disclosed in Fig. 1 this result is attained by a relatively separated but non-lapped relation of said portions, such disposition permitting a considerable range of movement of one portion with respect to the other. Obviously such portions may overlap and still be capable of a relative play.

The tubular spring-metal ring 10 is engaged by the securing provision somewhat contiguous to the edge portion 12, whereby the said ring will be so held that all that resilient part thereof which extends from such engagement to and includes the edge portion 11 will be free to move under the compression and expansion conditions induced during use, the amplitude of such movements increasing in the direction of said edge portion, at which latter part it is the greatest, and thus providing adequate elasticity for

that part of the ring which is more immediately associated with the tread. It will be noted that with the tubular ring 10 secured as described the portion 11 occupies a position at the side of the transverse horizontal axis of the tube opposite to that where the tread is located, with the result that the free resilient part of the ring is disposed to be sensible of compression exerted at any point throughout a comparatively extended radius. This feature insures the ring performing its cushioning and other functions to a wide extent irrespective of deviations of the wheel from a perpendicular position, such deviations being due to road variations and other causes.

If desired, the free resilient part of the ring 10 can have attached thereto, readily detachable or otherwise, a supplemental spring-metal section 13, extending circumferentially around the ring and preferably having its ends united to accord with the continuous character of the ring. This supplemental section 13 is corrugated and is shown of such width that besides providing for the corrugated feature referred to and normally affording a transversely-extended clearance space 14 between it and the resilient part of the ring the edge portions 15, 16 of said section bear upon and are secured to said free resilient part at points approximate to the transverse horizontal axis of the ring, small machine-screws 17 being indicated as one form of securing means. The section 13 may present a plurality of corrugations, the arrangement illustrated, providing for central and side corrugations 18, 19, and 20, respectively, longitudinally disposed and in parallel relation. The corrugations need not necessarily extend longitudinally nor be parallel.

The contour and relatively excessive area of the section 13 render it stiffer than the resilient part of the ring, and hence when compression is encountered said section through its connections with said part causes the latter to yield, and thus afford an easy cushioning effect. As the compression further increases the section will be forced back upon the free part, said section meanwhile becoming more rigid and at the same time causing the free part of the ring to yield, but to an extent less than previously. Ultimately under accumulative compression the free part will have become sufficiently unyielding to resist further movement by the section, whereupon inwardly-extending bends 21 of the latter intermediate of the central and side corrugations will bear upon the now comparatively rigid free part and result in the flexible material embodied in the tread portion of the envelop or shoe 22 flowing and accommodating itself to the general outline externally presented by said section, where- 65 by said tread portion will acquire for the

time being pronounced alternate ridges and depressions, which will greatly enhance the tractive capacity of the tread.

The securement of the ends of the section 13 in the manner stated provides for said section moving bodily with the free part of the ring, while the relative sliding of the section ends on the surface of said free part is prevented, and hence chafing and heating from this cause are avoided. It will also be appreciated that the absence of the corrugated feature from the free part obviates any tendency of the spring portions of both the section and said free part from becoming under any compression mutually engaged or interlocked, which latter condition would interfere with or tend to negative the freedom of spring movement of which both said section and said part are more or less independently capable.

While any suitable envelop or covering may be employed in connection with a tubular spring-metal ring possessing all or some of the novel characteristics previously described, the envelop or covering illustrated is in the form of a shoe 22 of yielding material, such as rubber or any of its elastic compounds. Such shoe may be of composite character and embody one or more thicknesses of canvas or other suitable fabric. The shoe is shown as generally comprising inner and outer layers 23, 24, united by vulcanization to firmly confine between them contiguous to the shoe-tread a transversely-extended and longitudinally-continuous armor 25, which should be of some material and so conditioned that while promoting the durability of the shoe it will at the same time be sufficiently flexible to permit the tread portion while under compression to conform to the corrugations and depressions of the supplemental metal section 13, as previously explained. One arrangement of such armor consists of a series of thin strips of cane or equivalent material closely woven and presenting diagonally-crossed, transverse, and longitudinally-extended strands.

It will be observed that the major thicknesses of material forming the shoe are present both at and adjacent to the tread portion, the latter being the part where increased thickness is important both for wear purposes and for augmenting the cushioning effect obtained in connection with the inclosed spring-metal ring. The tread portion in Fig. 1 normally presents a moderately-curved surface, which is prolonged at each side by the integral lateral enlargements 26, such configuration of tread upon a slight compression providing practically a broad flat cushion-bearing for the wheel conducive to the easy travel of the vehicle. The corrugations 18, 19, and 20 of the supplemental metal section 13 by bearing against the interior surface of the inner layer 23 contribute

to support and brace the tread portion of the shoe.

The edge portions 27, 27, constituting the base of the shoe, are enlarged and of the configuration shown—that is to say, they present inner downwardly-converging faces 28, 28 and outer shoulders 29, 29, the latter and the under sides of the portions 27 being rounded to adapt the lower parts of said portions for snugly conforming within the metal rim 30, with the overturned curved edges 31 thereof taking over and engaging the shoulders. Tapering blocks or sections 32 are interposed between the portions 27, so that the latter are mutually spread to maintain them engaged by the rim, and for rendering such portions sufficiently rigid for such purpose longitudinally-disposed filling-pieces 33 are inclosed within the portions 27. These filling-pieces may be of a cross-sectional shape, so that they will generally accord with the cross-sectional character of the base portions of the shoe and insure said portions being forced into their engaged positions without liability of their becoming buckled or not being uniformly held. The pieces 33 may be introduced in position by insertion, or they may be molded in the shoe during the manufacture of the latter. Said pieces can be of any satisfactory material, such as rubber stiffer than that otherwise embodied in the shoe, or compressed fiber, metal, or tough wood may be used.

The blocks 32, which will preferably be of some durable rigid material—such as wood, compressed fiber, metal, or the like—need not occupy the full depth of the space between the shoe portions 27, but can primarily stop somewhat short of the rim-bottom to permit subsequent downward movement of said blocks in order to tighten the shoe portions in their engaged positions in the operation of bolting the parts together or in the event of said portions becoming loose through wear, shrinkage, or other cause. Said blocks are regularly spaced around the wheel and form, in connection in the tubular spring-metal ring, shoe-base, and rim, a circular series of intermediate spaces 34. The ring, shoe, blocks, rim, and the felly 35 are all rigidly clamped together in the operative relation disclosed in the drawings by bolts 36, which extend through appropriate openings in the ring, blocks, rim, and felly and firmly clamp the same together through the medium of the bolt-heads 37 and securing-nuts 38 on the externally-projecting portions of the bolt-shanks. Each bolt-head may be conditioned to bear directly upon the inner part of the ring 10; but in the arrangement shown an arched section 39, of metal, is provided for each bolt and has its parallel lower edges bearing on the interior surface of the ring, so that said section spans the contiguous bolt-opening in the ring to the end that the bolt

will extend through a somewhat elongated longitudinal slot 40 in the section, and the bolt-head, which is transversely curved, will bear on the top of said section. The bolt-openings 41 and 42 in the ring 10 and in each block 32, respectively, are also in the form of longitudinal slots, but may be of successively decreased length to avoid undue cutting away of the parts in which said slots are formed, and yet provide slots adequate for the convenient introduction and removal of the particular bolt employed.

The description immediately preceding, including the reference to the character and relation of the slotted sections 39, blocks 32, and ring 10, will render the manner in which the several parts are assembled and bolted together readily comprehended. With one of the portions 27 of the shoe-base disengaged and turned back to expose the continuous opening presented in the tube side between the edges 11, 12 the successive bolts can, while each is held in a horizontal position through the instrumentality of an appropriate tool, be laterally introduced within the tube, after which, said bolt can be so manipulated that its shank will be caused to descend through the several slots of the section 10, ring and block beneath, and enter and move within the openings in the rim and felly until it projects sufficiently external to said felly to permit the bolt to be drawn fully into position. The removed portion of the shoe can then be replaced within the rim, the ring 10 and blocks being sufficiently loose for this purpose, after which the nuts 38 are applied to draw the bolts home, and thus securely clamp all the parts together. Manifestly the parts can be readily disconnected by simply reversing the series of operations immediately before described.

As the positive retention of the bolts against accidental loosening is of the highest importance, the nuts 38 have a lock associated therewith. This lock may involve various forms, the provision disclosed for such purpose consisting in providing each bolt with right and left hand screw portions, one of which is engaged by the nut 38, while the other takes a nut 48, preferably of smaller size to facilitate its independent adjustment or removal and which will operate to prevent the companion nut 38 from turning in a manner well known in other applications of this device.

Still referring to the construction illustrated in Figs. 1 and 2, each bolt has an axial duct 44 therethrough and establishing communication between the atmosphere and the tire interior. Vertically-elongated openings 45 in each bolt intersecting the duct therein likewise provide for atmospheric communication with the spaces or chambers 34 by way of the slot 42 and passage presented by the clearance immediately below each block.

The various ducts, openings, and passages of the wheel serve for the admission of air to the tube interior and chambers 34 to reduce the heat engendered through frictional stress of certain of the parts and working of the movable portions of the construction during the travel of the wheel. Clearly compression experienced by said movable portions will act to expel a considerable volume of air from the tire interior and cause the discharge of said air from the openings at the ends of the bolt-shanks, the currents of air under pressure thus moving through the bolt-ducts acting to withdraw air from the chambers 34 on the well-known principle of the ejector. The succeeding expansion of the movable portions will effect the induction of fresh and cooler air for absorbing and subsequently carrying off a considerable percentage of any heat that may be developed. The cooling effect of the air will be appreciably augmented by the presence of numerously-distributed apertures 46 47 in the free part of the ring and supplemental section 13, respectively, and alternately disposed to secure a baffling circulation of the air in the immediate vicinity of the tread.

When the wheel is in service, the alternate expulsion and induction of the air proceed continuously around the entire construction, the advantages ensuing from each expulsion and induction being experienced at the period when and point where most required—*i. e.*, a part of the construction which either is or immediately has been in bearing relation with the surface over which the wheel is traveling. The objectionable admission of dirt and other foreign matter to the ducts, &c., can be obviated by the application of a suitably-conditioned cap 49 to the projecting end of each bolt.

In Fig. 3 the peculiarly-functioned split tubular ring 10^a is shown as being embodied in connection with a tire structure of the pneumatic type. In this construction an inflatable tube 50 is confined within the tubular ring, and in order to provide for the convenient securement of the parts together and at the same time maintain the integrity of the air-tight character of the tube 50, the ring 10^a, block 32^a, rim 30^a, and felly 35^a contain longitudinal slots 54, 55, 56, and 57, respectively, vertically registering with each other, as indicated in Fig. 8. The bolts 36^a in this embodiment of the invention are solid, and each has a transversely-extending head 37^a, rounded on its upper and lower sides and of such size that with the bolt held to present said head longitudinally at the inner side of the felly such head and bolt can be passed successively through the felly, rim, block, and ring and then by a quarter-turn of the bolt its head be caused to span the slot in the ring to become engaged with the latter, and thus be positively retained against with-

drawal. All of the bolts having been similarly engaged, the base portion 27^a of the shoe 22^a, which has meanwhile been removed from the rim, is replaced, the nuts 38^a 48^a applied to firmly draw and retain the parts together, after which the tube 50 can be inflated, any of the ordinary devices being provided for such purpose.

Fig. 4 discloses a cushion form of the invention adapted for heavy service. In this arrangement the bolts 36^b contain the axial ducts 44^a to permit the expulsion and induction of the air with reference to the interior of the tubular ring 10^b. For augmenting the strength of the construction the air-chambers 34 are dispensed with, the blocks 32^b being arranged in close succession and bearing on the metal band-rim 30^b. The base portions 27^b 27^b of the shoe 22^b are held by the independent clamp-plates 58 58, conjointly bolted to the felly 35^b independent of the other parts, thus permitting one of the base portions 27^b to be displaced or the shoe to be completely removed without disturbing the connected relation of said other parts.

The construction illustrated in Fig. 5 is in most respects similar to that shown in Figs. 1 and 2, the tread portion of the shoe 22^c being of different configuration and rounded to a more pronounced degree to adapt the wheel 95 for a different character of service.

In Fig. 6 the shoe 22^d is of the rounded type disclosed in the preceding figure and is shown as being employed in connection with a cushion construction embodying the tubular spring-metal ring 10^c and inner tube 50^b, the parts being secured by the bolts 36^c, conditioned and applied in a manner similar to that described with reference to Fig. 3.

Fig. 7 illustrates another cushion construction more particularly designed for heavy traffic and comprises independent clamp-plates 59 59^a for combining the base portions 27^c 27^c of the shoe. This figure generally discloses novel means for fastening the clamp-plates to the felly 35^c independently of the other parts, the bolts forming part of said novel means being each provided near one end with a shoulder 60, against which the adjacent plate 59^a is held by a nut 61, engaged with a short threaded stem 62 of the bolt, projecting through a suitable opening in said plate. The other end portion 63 of each bolt contains a slot 65, which is of such length that an end portion thereof is designed to be within the opening of the adjacent clamp-plate 59 when the latter is held against the felly. Now by the insertion of a suitable wedge 64 in the slot both plates will be drawn and firmly held against the felly, one edge of the wedge bearing against the metal at the outer end of the slot, while the other edge bears against the exterior face of the clamp-plate. The retention of said wedge 130

can be assured by the insertion of a split key 66 through the smaller portion of the wedge. The excess of the slot 65, or that part thereof which is within the bolt-opening, admits of a further forcing movement of the wedge when required to take up any looseness of the clamp-plates that might be occasioned by shrinkage of the felly, wear of the parts, or through any other cause. Looseness through shrinkage is regarded as a remote contingency, as the felly material in the wheels of the present period is so well seasoned that if any change occurs it is more liable to be due to a swelling of the material, a condition which would obviously conduce to the more rigid clamping of the plates of the felly.

When it is desired to remove one of the base portions 27° of the shoe or detach the shoe completely, the key 66 is pulled out and the wedge withdrawn, whereupon a slight blow inward on the end of the slotted portion of the bolt will shift the latter relative to the plate 59 and felly 35° and cause the bolt-shoulder to displace the plate 59° to such extent as will result in the release of the adjacent base portion 27° of the shoe. If the latter is to be completely detached, the bolt is after the removal of the released portion 27° then shifted in the opposite direction, which will manifestly occasion the release of the other base portion.

The manifold features of importance, and consequent advantages involved in the present improvements, are regarded as being so evident from the foregoing description and accompanying drawings that further explanation is not deemed necessary.

Having now described my invention, what I claim as new, and desire to secure by Letters Patent, is—

1. A tire comprising a tubular element of stiff resilient material, longitudinally disposed and perforated contiguous to the tire-tread, such element being divided at one side to present edge portions one of which is adapted for free movement with respect to the other.

2. A tire comprising a tubular element of spring metal, longitudinally disposed and perforated contiguous to the tire-tread, such element being divided at one side to present edge portions one of which is adapted for free movement with respect to the other.

3. A tire comprising a tubular element of stiff resilient material, longitudinally disposed and perforated contiguous to the tire-tread, such element being divided at one side to present edge portions one of which is adapted for free movement with respect to the other, and provision for positively securing the inner portion of the element in position.

4. A tire comprising a tubular element of spring metal, longitudinally disposed and

perforated contiguous to the tire-tread, such element being divided at one side to present edge portions one of which is adapted for free movement with respect to the other, and provision for positively securing the inner portion of the element in position.

5. A tire comprising a perforated tubular ring of stiff resilient material, longitudinally disposed, such ring being longitudinally divided at one side to present edge portions one of which is capable of free movement with respect to the other, and provision for positively securing the inner portion of the ring in position.

6. A tire comprising a perforated tubular ring of spring metal, longitudinally disposed, such ring being longitudinally divided at one side to present edge portions one of which is capable of free movement with respect to the other, and provision for positively securing the inner portion of the ring in position.

7. A tire comprising a flexible casing and a perforated tubular element of stiff resilient material, longitudinally disposed within the casing and contributing to form an externally-located air-space communicating with the interior of the tubular element, the latter being divided at one side to present edge portions one of which is capable of a free movement with respect to the other.

8. A tire comprising a flexible casing and a perforated tubular element of spring metal, longitudinally disposed within the casing and contributing to form an externally-located air-space communicating with the interior of the tubular element, the latter being divided at one side to present edge portions one of which is capable of a free movement with respect to the other.

9. A tire comprising a flexible casing and a perforated tubular ring of stiff resilient material, longitudinally disposed within the casing and contributing to form an externally-located air-space communicating with the interior of the tubular ring, the latter being divided at one side to present edge portions one of which is capable of a free movement with respect to the other.

10. A tire comprising a flexible casing and a perforated tubular ring of spring metal, longitudinally disposed within the casing and contributing to form an externally-located air-space communicating with the interior of the tubular ring, the latter being divided at one side to present edge portions one of which is capable of a free movement with respect to the other.

11. A tire comprising a flexible casing and a perforated tubular ring of stiff resilient material, longitudinally disposed within the casing and contributing to form an externally-located air-space communicating with the interior of the tubular ring, the latter being divided at one side to present edge portions one of which is capable of free movement.

with respect to the other, and provision for positively securing the inner portion of said ring in position.

12. A tire comprising a flexible casing and 5 a perforated tubular ring of spring metal, longitudinally disposed within the casing and contributing to form an externally-located air-space communicating with the interior of the tubular ring, the latter being divided at 10 one side to present edge portions one of which is capable of free movement with respect to the other, and provision for positively securing the inner portion of said ring in position.

13. A tire comprising a perforated element 15 of stiff resilient material, longitudinally disposed, and a supplemental section of stiff resilient material external to said element.

14. A tire comprising an element of stiff 20 resilient material longitudinally disposed, and a perforated supplemental section of stiff resilient material, external to said element.

15. A tire comprising a perforated element 25 of stiff resilient material, longitudinally disposed, and a perforated supplemental section of stiff resilient material, external to said element.

16. A tire comprising a perforated element 30 of stiff resilient material, longitudinally disposed, and a perforated supplemental section of stiff resilient material, external to said element, the perforations of said element and section being differentially located with respect to each other.

17. A tire comprising a perforated tubular element of stiff resilient material, longitudinally disposed, and a supplemental section of stiff resilient material, external to 40 said element.

18. A tire comprising a tubular element of stiff resilient material, longitudinally disposed, and a perforated supplemental section of stiff resilient material external to said element.

19. A tire comprising a perforated tubular element of stiff resilient material, longitudinally disposed, and a perforated supplemental section of stiff resilient material external to 45 said element.

20. A tire comprising a perforated tubular element of stiff resilient material, longitudinally disposed, and a perforated supplemental section of stiff resilient material, external to 50 said element, the perforations of said element and said section being differentially located with respect to each other.

21. A tire comprising a perforated tubular element of stiff resilient material, longitudinally disposed and divided at one side to present edge portions one of which is adapted to move relative to the other, and a supplemental section of stiff resilient material external to said element.

22. A tire comprising a perforated tubular

element of stiff resilient material, longitudinally disposed and divided at one side to present edge portions one of which is adapted to move relative to the other, and a perforated supplemental section of stiff resilient material external to said element. 70

23. A tire comprising a perforated tubular element of stiff resilient material, longitudinally disposed and divided at one side to present edge portions one of which is adapted to move relative to the other, a supplemental section of stiff resilient material external to the tubular element, and provision for positively securing the inner portion of said element in position. 75

24. A tire comprising a perforated tubular element of resilient material, and a casing and interposed supplemental element of yielding material contributing to form in connection with the tubular element, an air-space external to said element, said supplemental section being perforated. 85

25. A tire comprising a perforated element of resilient material, longitudinally disposed, and a corrugated element of resilient material external to said element. 90

26. A tire comprising an element of resilient material, longitudinally disposed, and a perforated corrugated element of resilient material external to said element. 95

27. A tire comprising an element of perforated resilient material, longitudinally disposed, and a perforated corrugated element of resilient material external to said element.

28. A tire comprising an element of perforated resilient material, longitudinally disposed, and a perforated corrugated section of resilient material contributing to form in connection with said element, an air-space external thereto, the perforations of the element and sections being differentially located with respect to each other. 100

29. A tire comprising an element of perforated flexible material, longitudinally disposed, and a corrugated section engaged with said element. 110

30. A tire comprising an element of perforated flexible material, longitudinally disposed, and a perforated flexible corrugated section engaged with said element. 115

31. A tire comprising an element of perforated flexible material, longitudinally disposed, a casing of flexible material and an interposed corrugated section engaged with said element. 120

32. A tire comprising a perforated flexible element longitudinally disposed, a casing of flexible material and an interposed corrugated and perforated section engaged with said element.

33. A tire comprising a flexible perforated tubular element longitudinally disposed and divided at one side to present edge portions one of which is adapted to move relative to the other, a corrugated section engaged with the other, a corrugated section engaged with 125 the other, a corrugated section engaged with 130

said element, and provision for positively securing said element in position.

34. A tire comprising a flexible tubular element longitudinally disposed and divided at one side to present edge portions one of which is adapted to move relative to the other, a perforated corrugated section engaged with said element, and provision for positively securing said element in position.

35. A tire comprising a flexible perforated tubular element longitudinally disposed, a yielding casing and an interposed corrugated section engaged with said element.

36. A tire comprising a flexible perforated tubular element longitudinally disposed, a yielding casing, an interposed corrugated section engaged with said element, and provision for positively securing said element in position.

37. A tire comprising a flexible perforated tubular element longitudinally disposed, a yielding casing, and an interposed corrugated perforated section engaged with said section.

38. A tire comprising a perforated tubular element longitudinally disposed, and a corrugated section contiguous to the tire-tread and having its edge portions engaged with the tubular element.

39. A tire comprising a tubular element longitudinally disposed, and a perforated corrugated section contiguous to the tire-tread and having its edge portions engaged with the tubular element.

40. A tire comprising a perforated tubular element longitudinally disposed, and a perforated corrugated section contiguous to the tire-tread and having its edge portions engaged with the tubular element.

41. A tire comprising a perforated tubular element longitudinally disposed, and a perforated corrugated section contiguous to the tire-tread and having its edge portions engaged with the tubular element, the perforations of said element and section being differentially located with respect to each other.

42. A tire comprising a perforated tubular element longitudinally disposed, a flexible casing and interposed perforated corrugated section, the latter having its edge portions engaged with the tubular element, the perforations of said element and section being differentially located with respect to each other.

43. A tire containing an air-space and adapted to contract and expand and contributing to form externally-located air-chambers, and tire-securing provision providing communications with said air-space and chambers, for normally permitting air-expulsion from, and induction with the same.

44. A tire comprising a longitudinally-dis-

posed element of stiff resilient material, a casing, a block in relation to the base of said casing, and a radially-adjustable provision engaged with said element for securing the latter, the block and the casing in position.

45. A tire comprising a flexible tubular element longitudinally disposed, a casing, a block in relation to the base of said casing, and radially-adjustable provision engaged with said element for securing the latter, the block and the casing in position.

46. A tire comprising a flexible tubular element longitudinally disposed, and divided at one side to present edge portions one of which is adapted to move relative to the other, a casing, a block in relation to the base of said casing, and radially-adjustable provision securing the tubular element, block and casing in position.

47. A tire comprising a flexible tubular element longitudinally disposed, a shoe having base portions with apposite converging faces, a wedge-block between said faces, and provision for securing the tubular element, block and base portions of the shoe, in position.

48. A tire comprising a flexible tubular element longitudinally disposed and divided at one side to present edge portions one of which is movable with respect to the other, a shoe having base portions with apposite converging faces, a wedge-block between said faces, and provision for securing the tubular element, block and base portions of the shoe, in position.

49. The combination with clamping-plates having shoe-engaging parts, of a shoe having a base provided with outer offsets, a bolt having a positive connection with one plate, said connections including a shoulder on the bolt, bearing against the inner side of said plate, and means cooperating with the other portion of the bolt for retaining the other plate in position.

50. The combination with clamping-plates having shoe-engaging parts, of a shoe having a base provided with outer offsets, a bolt having one end portion slotted and the other end portion positively connected with the adjacent plate, said connection including a shoulder on the bolt bearing against the inner side of said plate, and a wedge engaged with the bolt-slot for retaining the other plate in position.

Signed at Jersey City, in the county of Hudson and State of New Jersey, this 25th day of August, A. D. 1905.

LEWIS H. BROOME.
